UNITED STATES PATENT OFFICE.

MARVIN C. REYNOLDS, OF CHICAGO, ILLINOIS.

BARREL-EMPTYING MACHINE.

1,357,003.

Specification of Letters Patent. Patented Oct. 26, 1920.

Application filed December 11, 1917. Serial No. 206,674.

To all whom it may concern:

Be it known that I, MARVIN C. REYNOLDS, a citizen of the United States, and a resident of Chicago, in the county of Cook and State of Illinois, have invented certain new and useful Improvements in Barrel-Emptying Machines, of which the following is a specification.

My invention relates to an improved barrel emptying machine particularly adaptable for removing such substances as butter, fats, waxes, etc., from barrels or casks. Heretofore it was necessary to remove such substances by hand, a very impractical and inefficient procedure. The object of my invention is therefore to produce a simple and efficient machine for removing the substance from barrels or casks.

On the accompanying drawings I show a machine which embodies the various features of my invention. On the drawings—

Figure 1 is a side elevational view,

Fig. 2 is a plan view,

Fig. 3 is a sectional view on plane 3—3,

Fig. 1,

Fig. 4 is an enlarged sectional view on plane 4—4, Fig. 1,

Fig. 5 is an enlarged plan view of the parts shown in Fig. 4, and

Fig. 6 is a cross-sectional view on plane 6—6, Fig. 3.

The machine is constructed to raise a filled barrel and support it in position with its axis horizontal, a substance removing tool being then driven through the barrel and the removed contents conveyed away from the machine.

Referring to the drawings, the supporting frame work for the machine comprises side frames 10 and 11 connected together as necessary by cross bars and braces to afford the necessary strength, the frame-work being preferably portable by being mounted on wheels 12. At the front of the machine an elevator structure is provided for receiving the barrel, raising it, and tilting it in a horizontal position. This elevator comprises a supporting platform 13, the back wall 14 and the diagonal side braces 15. At the upper corners of the wall 14 pins 16 and 17 extend laterally for engaging in the vertical guide slots 18 and 19 formed in the vertical beams 20 and 21 forming part of the machine supporting frame-work. The pins 16 and 17 are oblong and when the elevator is down

they are at the bottoms of the slots 18 and 19, and when the elevator has been raised they abut against the tops of the slots and so limit the vertical movement, the slots at their tops having the lateral extensions 22 forming shoulders 23 on which the pins rest after swing of the elevator to horizontal position.

Describing the means for raising the elevator and swinging it to horizontal position, a bail 24 is secured at its ends to the sides of the elevator platform, a cable 25 extending from the bail around the guide sheaves 26 and 27 and around a drum 28. When the elevator is down and the drum 28 rotated, the elevator is first raised until it is stopped by the engagement of the pins 16 and 17 with the upper ends of the slots. Then further pull on the cable will swing the elevator to horizontal position, the pins 25 acting as pivots and entering the slot extensions 22 to rest on the shoulders 23 to support the elevator in horizontal position. In order to lock the elevator in horizontal position independently of the cable and drum, a detent bar 29 is provided, this bar being pivoted at its outer end to the back wall of the elevator and sliding over the cross bar 30 as the elevator is raised, and when the elevator has been swung into horizontal position the detent notch 31 receives the edge of the bar 30, the elevator being then held in horizontal position by the detent bar and the pins 16 and 17 which rest on the shoulders 23. In order to readily release the detent bar to permit return of the elevator I provide tripping mechanism.

As shown, a lever 32 is pivoted at 33 and has the tripping tongue 34 extending upwardly below the end of the detent bar, a link 35 connecting the free end of the lever with a treadle lever 36 pivoted to the machine frame at 37. Upon stepping against the front end of the treadle lever the lever 32 is swung upwardly to bring the tongue 34 against the end of the detent bar to raise the bar sufficiently to release it from the cross bar 30. A spring 38 tends to hold the tripping mechanism away from the detent bar.

Mounted at the top and at one side of the machine frame-work is a driving motor M, and bearing frames 39 for the main drive shaft 40. At the other side of the frame-work the counter shaft 41 is journaled in

suitable bearings 42, a belt 43 connecting the shaft with the main shaft. At the front end of the shaft 41 the drum 28, for raising the elevator, is mounted, suitable clutch mechanism 44 being operated by a lever 45 to control the driving connection of the drum with the shaft. Suitable brake mechanism 46 controlled by a lever 47 is also provided for controlling the unwinding movement of the drum when it is unclutched from the shaft when the elevator is to be lowered. When the clutch is thrown in and the brake released the drum will be rotated and the elevator raised. When it is desired to lower the elevator the brake is set and the drum unclutched from the shaft and then by manipulating the brake the elevator can be gradually restored to its vertical position ready to receive another barrel. In order to reduce the strains on the hoisting drum mechanism and to prevent accident should the drum cable break or become disconnected, I provide a drum 48 extending crosswise of the machine for a chain or cable 49 whose front end extends over the sheave 50 and is secured to the elevator bail 24, a weight w being secured to the other end of the chain. A ratchet wheel 51 is secured to the drum 48 and on a rod 52 is pivoted the pawl 53 for engaging with the ratchet wheel to prevent unwinding of the drum after any winding up movement thereof, the weight turning the drum 48 as the elevator rises. If anything should happen to the hoisting mechanism during raising of the elevator with the heavy barrel thereon, the ratchet drum arrangement will lock the elevator and prevent sudden falling thereof. In order to disconnect the ratchet drum mechanism to permit lowering of the elevator I provide tripping mechanism for the pawl 53. As shown, a rod 54 is pivoted in brackets 55 and has its inner end 56 deflected laterally into position below the pawl, the outer end 57 of the lever extending laterally in the opposite direction and connected with an actuating lever or cord 58, a pull on which will rotate the tripping lever to raise the pawl from the ratchet wheel.

Describing now the mechanism for removing the contents from a barrel B after it has been elevated into horizontal position on the machine, a shaft 59 is arranged on the machine in line with the barrel axis and carries at its front end a suitable tool T for cutting out the barrel contents. The rear end of the shaft is threaded and extends through the threaded bushings 60 and 61 supported in the bearing frames 62 and 63 mounted on the rigid cross bars 64 and 65 connecting the side frames of the machine. Between the bushings 60 and 61 a pulley 66 receives the shaft and has a key 67 for engaging in the key slot 68 cut in the

threaded end of the shaft so that when the pulley is turned the shaft will be turned therewith in the threaded bushings 60 and 61 and the shaft will be shifted longitudinally forwardly to carry the tool T into 70 and through the barrel. In front of its threaded section the shaft passes through the bearing frame 69 between collars 70 and 71 secured to the shaft, and this frame 69 is secured to a cross beam 72 which at its ends 75 has guide tongues 73 and 74 extending through the guide slots 75 and 76 in the guide bars 77 and 78 secured to the framework sides 10 and 11. As the shaft is turned the beam 72 travels forwardly and supports 80 the shaft to keep the tool T aligned in the barrel. The tool may be of any suitable construction for cutting, shaving, or loosening the barrel contents. Figs. 3 and 6 show a simple construction. A sheet metal disk 85 79 is secured to the end of the screw shaft by means of brackets 80, and the disk has one or more radially extending slots 81 adjacent one edge of which the disk material is deflected outwardly to form a blade 82 90 whose outer edge is sharpened. The disk will therefore operate like a bit to cut the barrel contents as the screw shaft is rotated, the shaved off slices or slabs passing forwardly through the slot 81 and out of the barrel. A trough 83 may be secured to the machine frame-work below the barrel mouth and constructed to discharge the material where desired.

Describing the driving mechanism for the screw shaft, a counter shaft 84 is journaled in bearing frames 85 and 86, forward and reverse pulleys 87 and 88 being pivoted on the shaft and connected by belts 89 and 90 with the pulleys 91 and 92 on the main drive shaft. 105 The shaft 84 has secured thereto a transmission pulley 93 which is connected by belt 94 with the pulley 66 on the screw shaft. Between the forward and reverse pulleys 87 and 88 suitable clutch mechanism is mounted 110 for connecting either pulley with the shaft. As shown, a clutch head 95 is slidable on the shaft by means of a clutch lever 96 pivoted at its upper end to a bracket 97. By means of suitable clutching mechanism 98 the pulley 88 will be connected with the shaft 84 for rotation and by means of clutching mechanism 99 the pulley 87 will be connected with the shaft depending upon what direction the clutch head 95 is shifted. At one end 120 of the beam 72 is a detent plate 100 against the rear side of which the end of the clutch lever 96 is yieldingly held by means of a spring 101, the lever being normally in neutral position with the tool T outside of the barrel entrance. For shifting the clutch lever into position to start the screw shaft a cord 102 is provided which extends around pulleys 103 to the front of the machine and provided with a grip 104. When the cord is 130

pulled the clutch lever 96 will be swung rearwardly and the clutch mechanism operated to cause rotation of the screw shaft in a direction to shift the tool into and 5 through the barrel. On the shelf 105 I pivot a latch lever 106 whose front end has the latch hook 107 for receiving and holding the clutch lever 96 when swung rearwardly to set the machine for forward drive of the 10 tool, a spring 108 tending to hold the latch in latching position. The latch lever has the arm 109 through which extends the rear end of a trip rod 110. This rod extends through the guide bracket 111 mounted on 15 the beam 72 and at its front end has the adjustable abutment 112. After pull on the cord 102 to swing the clutch lever 96 into the latch lever 106, the screw shaft will be rotated and the tool shifted forwardly into 20 and through the barrel, the beam 72 traveling forwardly with the shaft. The front wall of the bracket 111 will reach the abutment 112 on the trip rod when the tool reaches the bottom of the barrel and then a 25 slight forward shift of the trip rod will swing the latch lever 106 to release the clutch lever 96 and the spring 101 will throw the lever past neutral and into forward position to disconnect the forward 30 driving mechanism and to connect in the reverse driving mechanism, the screw shaft being then shifted back toward normal position. As the beam 72 travels rearwardly with the screw shaft its detent plate 100 35 will encounter the clutch lever and will swing it rearwardly until the lever assumes its normal neutral position, whereupon the driving stops and the screw shaft come to rest in neutral position. The reverse pulley 88 is preferably smaller than the forward pulley 87 in order that the shaft is 40 restored to neutral position in a short time.

Briefly summing up on the operation, a barrel is placed on the lowered platform 45 and the clutch lever 45 pulled to clutch in a hoisting drum 28 whereupon the elevator is raised and tilted to bring the barrel with its axis in line with that of the screw shaft 59. During raising of the elevator the 50 weight *w* rotates the drum 48 and the pawl locks the drum so as to prevent sudden dropping of the barrel and elevator should the hoisting apparatus fail. The cord 102 is then pulled and the clutch lever 96 swung 55 rearwardly from its neutral position to cause clutching of the pulley 87 to the shaft 84 and then upon driving of the pulley 66 the screw shaft 59 will be rotated and shifted longitudinally forwardly, the rotating tool 60 T passing into the barrel and cutting out the contents. When the clutch lever 96 is 65 swung rearwardly it is received and held by the latch 106 and the screw shaft continues to rotate forwardly and to advance until the bracket 111 strikes the abutment nut 112

on the trip rod, the resulting rotation of the latch 106 releasing the clutch lever 96 which is thrown forwardly by the spring 101 through neutral position and into forward position to cause clutch 98 to become 70 effective whereupon by means of the cross belt 90 and the small pulley 88 the screw shaft will be shifted rearwardly to withdraw the tool from the barrel. As soon as the abutment plate 100 on the traveling support 72 encounters the clutch lever 96 it carries it back into neutral position to release the clutch 98, whereupon the screw shaft stops with its tool T in normal position in front of the barrel. During withdrawing 75 movement of the tool from the barrel any of the contents still remaining will be pulled out. To remove the empty barrel, the operator steps on the treadle to raise the tongue 34 and to release the detent bar 29, 80 and he also pulls on the cord 59 to release the counter weight drum 48 from the pawl 53. Then by operating the brake 47 on the hoisting drum, the elevator with the empty barrel can be gradually dropped back to the 85 floor and the empty barrel removed. The machine being on wheels, it can be readily moved about, and by a suitable chute 83 the discharged material can be guided to and discharged where desired. 95

I do not desire to be limited to the exact construction, arrangement and operation shown and described as modifications are no doubt possible which would still come within the scope of the invention. 100

I claim as follows:

1. In elevating mechanism for barrel emptying machines, the combination of a supporting frame, an elevator structure normally resting on the floor to receive a barrel in vertical position, said frame having vertical slots, shoulders at the upper ends of said slots, pins extending from said elevator structure into said slots, hoisting mechanism connected with the outer end of said elevator structure for first raising said elevator structure until the pins reach the upper ends of said slots and rest on said shoulders and for then tilting the elevator structure to bring the barrel into horizontal position, and a detent bar coöperating with said pins to hold the elevator structure in tilted position independent of said hoisting mechanism. 110 115

2. In elevating mechanism for barrel emptying machines, the combination of a supporting frame, an elevator structure normally resting on the floor to receive a barrel in vertical position, said frame having vertical slots, shoulders at the upper ends of said slots, pins extending from said elevator structure into said slots, hoisting mechanism connected with the outer end of said elevator structure for first raising said elevator structure until the pins reach the up- 120 125 130

per ends of said slots and rest on said shoulders and for then tilting the elevator structure to bring the barrel into horizontal position, a detent bar coöperating with said pins to hold the elevator structure in tilted position independent of said hoisting mechanism, and tripping mechanism for releasing said detent bar.

3. In elevating mechanism for barrel emptying machines, the combination of a supporting frame, an elevator structure for receiving a barrel in upright position, hoisting mechanism for first hoisting said elevator structure and then tilting it to bring the barrel thereon into horizontal position, a

drum, a cable engaging said drum, one end of said cable being connected with said elevator structure, a weight on the other end of said cable, a ratchet wheel on said drum, a pawl, said weight rotating said drum and 20 said pawl coöperating with said ratchet wheel during raising of the elevator structure by the hoisting mechanism to lock said elevator structure against return movement independently of said hoisting mechanism, 25 and means for releasing said pawl.

In witness whereof, I hereunto subscribe my name this 8th day of December, A. D., 1917.

MARVIN C. REYNOLDS.
